PRESSURIZED DISPENSING CONTAINER

Erwin P. G. Rahn, Pittsford, and Saul A. Babbin, Henrietta, N.Y., assignors to Wallace & Tiernan Inc., East Orange, N.J., a corporation of Delaware

Filed July 7, 1966, Ser. No. 2,971

Term of patent 14 years

(Cl. D58—17)

FIG. 1

FIG. 2

FIG. 3

FIG. 4

FIG. 1 is a rear elevational view of a pressurized dispensing container, embodying our new design;

FIG. 2 is a front elevational view;

FIG. 3 is a top plan view; and

FIG. 4 is a fragmentary view of the upper portion looking from the left of FIG. 2.

The characteristic features of our design for the pressurized dispensing container, that is disclosed, reside in a waisted cylindrical sidewall with its narrow waist above the midpoint of the sidewall in combination with a hemispherical apertured cavity in the front top portion of the sidewall and a waisted juncture line, that is defined at the top of the container by a flat top wall and a valve actuator in a recess of the top wall and a shallow elongated notch at the top of the sidewall, conforming to the waisted cylindrical configuration of the sidewall of the container.

We claim:

The ornamental design for a pressurized dispensing container, as shown and described.
